UNITED STATES PATENT OFFICE

153,330

DESIGN FOR A PERCOLATOR

Robert B. Wemyss, Louisville, Ky., assignor to
Reynolds Metals Company, Richmond, Va., a
corporation of Delaware

Application June 4, 1946, Serial No. 130,369

Term of patent 7 years

(Cl. D44—26)

To all whom it may concern:

Be it known that Robert B. Wemyss, a citizen of the United States, residing in Louisville, county of Jefferson, State of Kentucky, has invented a new, original, and ornamental Design for a Percolator, of which the following is a specification, reference being had to the accompanying drawing, forming part thereof, this application being a continuation-in-part of application filed November 28, 1944, Serial No. 116,586, now abandoned.

Fig. 1 is a side elevational view of a percolator, showing my new design,

Fig. 2 is a top plan view thereof, and
Fig. 3 is an elevational view thereof, slightly in perspective, taken at right angles with Fig. 1.

I claim:

The ornamental design for a percolator, substantially as shown.

ROBERT B. WEMYSS.
